INVENTOR

Francis H. Stillman

UNITED STATES PATENT OFFICE.

FRANCIS H. STILLMAN, OF BROOKLYN, NEW YORK.

HYDRAULIC PUNCH.

SPECIFICATION forming part of Letters Patent No. 507,666, dated October 31, 1893.

Application filed April 1, 1892. Serial No. 427,404. (No model.)

To all whom it may concern:

Be it known that I, FRANCIS H. STILLMAN, a citizen of the United States, residing in the city of Brooklyn, county of Kings, and State of New York, have invented new and useful Improvements in Portable Hydraulic Punches, adapted to be employed in punching holes in the webs of railroad-rails, of which the following is a specification.

10 This invention relates to improvements in portable, hydraulic punches adapted to be employed in punching bolt-holes for fish plates in the web of railroad rails after the rails are laid upon the cross-ties, and rendered

15 adjustable so as to punch holes centrally and in line in webs of various widths as will be hereinafter described.

Figure 1, represents a sectional side elevation showing a portion of the casing broken away to illustrate the interior mechanism, and the manner of withdrawing the punch quickly from the web of a rail after punching a hole therein, and an end view of a rail in position to be punched. Fig. 2, is a cross section through the overhanging, hooked end, extending from the casing showing an adjustable and removable die mounted therein, in elevation—and a sectional view of an adjustable plate by which the punch may be

20 adjusted up and down so as to punch holes centrally and in line in webs of varying widths. Fig. 3, is an elevation of the rear end of this portable, hydraulic, hand punch to show the manner of operating the hydraulic

25 pump, and withdrawing the punch from a web. Figs. 4 and 5, represent respectively a side elevation and cross section through the line X. X. of a shaft having cogs therein to take into corresponding cogs formed in the

30 side of the piston-rod by means of which the punch, secured thereto, may be quickly withdrawn from a web after having punched a hole therein as shown in Fig. 6.

Similar letters of reference indicate corresponding parts throughout the several views.

In order to adapt a hand punch, operated by a hydraulic pump and render it available in punching bolt-holes, for the fish-plates, in the web of railroad rails after the rails are laid upon the cross-ties, the first importance in actual practice is to reduce the instrument

to the minimum weight consistent with the strength required in order that it may be carried by hand along the track and quickly 55 adjusted to and removed from the rails, and to arrange the hydraulic pump by which it is to be operated in position with reference to the movement of the piston carrying the punch, that said pump may be operated independent of obstructions along the track, 60 and to reduce the length of the pump to the utmost limit. To effect these objects that part A. of the casing to which an ordinary piston C. and piston-rod B. are fitted, and to which 65 piston-rod a punch E. is secured, is reduced to a length admitting only of the movement back and forth of the punch E. required to pass through the webs, the hydraulic pump F. being secured perpendicularly to the casing A. 70 as shown in Fig. 1, in which perpendicular position said pump may be operated free of all obstructions along the rails.

To limit the length of the overhanging hooked end or jaw G. to the utmost and admit of introducing the tread H. of a rail between its inner surface and the end of the punch E., this hooked end is fitted with a removable and adjustable die J. which is to be removed from its seat when the tread H. of a 80 rail is to be introduced, and replaced as shown in Figs. 1. and 2. when a web is to be punched, this die being retained in position by means of a hooked latch N. and stop-pin O—thus it will be seen that by the above described description and arrangement of the various parts constituting this punch, a portable and useful hand implement adapted to punching holes for fish-plates in the web of railroad rails is produced, and rendered adjustable to the various widths of webs to be punched.

To withdraw the punch E. quickly from the web to the position as shown in Fig. 1, a shaft L. is fitted to the casing A. provided with 95 cogs R. taking into corresponding cogs P. formed in the upper side of the piston-rod B., said shaft L. being operated to withdraw the piston, with the punch E. secured thereto, by means of a lever T. in the usual manner of 100 operating similar mechanism.

An ordinary hydraulic pump and cistern F. is mounted upon and secured to the upper side of the casing A. by which the piston-rod

B. carrying the punch E. is to be operated in punching, the power-imparting fluid passing therefrom through a channel V. into the cylinder between the piston C. and cylinder head I. consisting of an ordinary screw-plug.

5 A base M. is formed on the lower-side of the casing A. in order to maintain this instrument in an upright position as shown.

To adjust this instrument so that holes may 10 be punched centrally, and accurately in line, in webs of varying widths, a plate S. is fitted to the lower side of this hook-shaped end G. in the space directly above the rail and adjustable up and down by means of bolts and 15 nuts U. so that the lower surface of this plate may rest upon the tread of the rail as shown in Fig. 1.

The operation of this portable, removable and adjustable punch in punching holes in 20 the web of railroad rails may be briefly described as follows: The die J. is removed from its seat and the overhanging hook-shaped end G. of the casing A. is placed so as to admit the thread H. of the rail in the space 25 between its inner face and the end of the punch E., the removable die J. is then replaced and locked in position by means of the stop O. and hooked latch N. as shown in Fig. 1.—the hydraulic pump is then operated 30 in the usual manner, the power-conveying liquid therefrom flowing into the cylinder through the channel V. and forcing the piston-rod B., carrying the punch E. forward to punch a hole in the web as shown. After a 35 hole is punched and the lever T in the end of the shaft L. is turned backward to withdraw, by means of the cog gearing, the punch from the web of a rail to the position shown

in Fig. 1., the die J. is removed from its seat and the instrument withdrawn from the rail to 40 repeat the operation as before described.

Having thus fully described my invention, what I claim therein as new, and desire to secure by Letters Patent, is—

1. A portable and adjustable hydraulic 45 punch adapted to punching holes in webs of varying widths of railroad rails after the rails are secured to the cross-ties consisting of an overhanging jaw—a punch and die therein—a hydraulic pump mounted upon and secured 50 perpendicularly to said jaw and an adjustable plate by which to raise and lower and adjust said jaw with respect to the rail substantially as herein set forth and shown.

2. A portable and adjustable hydraulic 55 punch adapted to punching holes in webs of varying widths of railroad rails after the rails are secured to the cross-ties consisting of an overhanging jaw to admit the rails—a punch and die therein and an adjustable plate secured to said overhanging jaw for adjusting the jaw with respect to the rails substantially as herein shown and described.

3. In a hydraulic punch adapted to punching holes in webs of varying widths of railroad rails in combination with the overhanging jaw thereof the adjustable plate carried upon the overhanging jaw and adapted to bear upon the surface of the rails to adjust said jaw up and down substantially as and for the purpose herein set forth.

FRANCIS H. STILLMAN.
